ENDLESS CONVEYER TYPE PACKING
MACHINE

Charles L. Doney, San Pedro, Calif.

Application October 11, 1937, Serial No. 168,528

4 Claims. (Cl. 226—96)

The invention relates to an endless conveyer type packing machine and more especially to a fish can packing machine.

The primary object of the invention is the provision of a machine of this character, wherein cleaned fish will be mechanically handled for the packing thereof in cans, these removable by a carrier in association with an endless feeder which through cooperation of plungers or pistons enables the successive filling of the cans upon the carrier, the machine being novel in construction, and enables the packing operation to be carried forth with dispatch and mechanically thereby eliminating hand labor for such purpose.

Another object of the invention is the provision of a machine of this character, wherein the construction thereof is duplex so that groups of cans can be filled and packed with fish, these groups being carried at opposite ends of the machine, and in this fashion assuring double capacity in the working of such machine.

A further object of the invention is the provision of a machine of this character, which is comparatively simple in its construction, thoroughly reliable and effective in operation, automatic in the working thereof, and inexpensive to manufacture and install.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is a side elevation partly broken away of a machine constructed in accordance with the invention.

Figure 2 is a horizontal sectional view taken longitudinally thereof.

Figure 3 is a fragmentary vertical longitudinal sectional view through the machine.

Figure 4 is a sectional view on the line 4—4 of Figure 1 looking in the direction of the arrows.

Figure 5 is a sectional view on the line 5—5 of Figure 4.

Similar reference characters indicate corresponding parts throughout the several views in the drawings.

Referring to the drawings in detail, the packing machine comprises a table A formed with a marginal upstanding flange 10 at its top 11 which is horizontally arranged, the top being rounded at opposite ends, while arranged perpendicularly at these ends are rotatable shafts 12

and 13, respectively, having splined or keyed thereto rotors 14 which are superposed with respect to rotary can carriers 15, these being integral with each other and splined or keyed to the said shaft. The rotors 14, each has peripherally formed therein spaced vertical substantially half circular shaped recesses 16 for accommodating packing cylinders 17, each formed near opposite ends with annular flanges 18 while between the said cylinders and pivoted to the flanges are 10 chain links 19 effecting an endless conveyer operating in a manner presently described.

Above the rotors 14 and upon stationary uprights 20 are sinuous cam tracks 21, these being disposed about the shafts 12 and 13, respectively, 15 for reciprocatory action of pistons or plungers 22 adapted for action within and out of the cylinders 17 under reciprocation thereof. The pistons or plungers 22 have their stems 23 operating through guides 24 on the outer ends of radial arms 25 20 extending from hubs 26 adjustably fixed to the shafts 12 and 13. The stems 23 at their upper ends have fitted thereto traction rollers 27 which operate in traction grooves 28 formed in the tracks 21.

Each carrier 15 is of circular formation having peripheral pockets 29 accommodating cans 30, these being fed into the pockets from the table top 11 and are empty when received in said pockets 20 for the subsequent filling thereof with 30 fish in the packing of such cans through the use of the machine.

The rotors 14 are formed with annular grooves or channels 31 for accommodating the flanges 18 formed on the cylinders 17 and in this manner 35 the endless conveyor is prevented from riding upwardly or downwardly in the travel thereof with relation to said rotors.

Interposed between the rotors 14 above the table top 11 is a platform 32 which eliminates the 40 sagging of the conveyer at the stretches between the rotors 14 when the said conveyer is in motion.

Next to opposite ends of the table 11 are upstanding rotary shafts 33 carrying horizontally disposed disk-like cutters 34, these working between the carriers 15 and the rotors 14 immediately above the upper open ends or tops of the cans 30 for the severing of the fish and preventing excess filling of the cans in the packing thereof, the fish being introduced into the cylinders 50 17, which are open at their upper and lower ends in any suitable manner at the time that the pistons or plungers 22 are without said cylinders and upon the lowering of these pistons or plungers the fillings of fish within the cylinders will be 55

5 packed automatically in the cans 30 fitting the carriers 15, the said carriers and rotors rotating in unison with each other, the shafts 33 being power driven in any suitable manner and likewise the shafts 12 and 13 are power driven in any desirable way.

10 The cylinders when engaged with the rotors 14 vertically align with the cans 30 in the carriers 15 and through activity of the pistons or plungers 22 on the downward strokes pack the 15 contents of the cylinders 17 into the cans 30 for the filling thereof.

15 The table top 11 holds the cans properly within the pockets 29 in the carriers 15, the introducing 20 of the fish after the cleaning thereof into the cylinders 17 may be had mechanically or by hand or otherwise.

20 The filling of the cans 30 for the packing thereof is had successively through a continuity of operation of the machine and in this manner assuring fast economical packing of the fish within the can which is subsequently cooked and sealed in any desirable manner. The filled cans are removed from the pockets 29 in the carriers 15 at 25 the table top 11 and empty cans substituted therefor, these empty cans being readily introduced into the pockets 29 from the table top 11 of the machine, there being no chance of the cans when empty or filled accidentally falling from the table 30 top. The platform 32 operates to close the lower open ends of the cylinders 17 to prevent droppings from these cylinders during the operation of the machine until the cylinders in single order reach the rotary cutters 34, one being at each end 35 of the table A. The platform 32 is suitably extended in any suitable manner about the rotors 14 so as to properly underlie the cylinders 17 occupying the pockets 29 when at opposite sides 40 of the cutters 34 to assure the closing of the lower ends of these pocketed cylinders until a meeting of the said cylinders in single order at the points of the cutters 34 therewith.

45 What is claimed is:

1. A machine of the character described comprising a table, rotors arranged at opposite ends of said table, an endless series of cylinders trained about said rotors, packing plungers reciprocatingly operated and movable within and without the cylinders at the points of the rotors, can carriers beneath said rotors for communication with

50

the cylinders when traveling about said rotors, and cutters operating between the rotors and said carriers for cutting material freed from the cylinders into the cans.

2. A machine of the character described comprising a table, rotors arranged at opposite ends of said table, an endless series of cylinders trained about said rotors, packing plungers reciprocatingly operated and movable within and without the cylinders at the points of the rotors, can carriers beneath said rotors for communication with the cylinders when traveling about said rotors, cutters operating between the rotors and said carriers for cutting material freed from the cylinders into the cans, and rotatable means supporting the rotors and carriers.

3. A machine of the character described comprising a table, rotors arranged at opposite ends of said table, an endless series of cylinders trained about said rotors, packing plungers reciprocatingly operated and movable within and without the cylinders at the points of the rotors, can carriers beneath said rotors for communication with the cylinders when traveling about said rotors, cutters operating between the rotors and said carriers for cutting material freed from the cylinders into the cans, rotatable means supporting the rotors and carriers, and means arranged between the rotors superposed with respect to the table for preventing sagging of the cylinders when traveling between said rotors.

4. A machine of the character described comprising a table, rotors arranged at opposite ends of said table, an endless series of cylinders trained about said rotors, packing plungers reciprocatingly operated and movable within and without the cylinders at the points of the rotors, can carriers beneath said rotors for communication with the cylinders when traveling about said rotors, cutters operating between the rotors and said carriers for cutting material freed from the cylinders into the cans, rotatable means supporting the rotors and carriers, means arranged between the rotors superposed with respect to the table for preventing sagging of the cylinders when traveling between said rotors, and cam trackage above said rotors and reciprocatingly operating the said plungers.
